SIGNALING SYSTEM AND APPARATUS
THEREFOR

Paul P. Horni, Newark, N. J.

Application April 27, 1938, Serial No. 204,527

3 Claims. (Cl. 177—361)

This invention relates to electric signaling and is particularly adapted for use in conjunction with fire alarms, and is a continuation in part of co-pending applications for Electric signaling system, Ser. No. 85,312, and for Electric signaling apparatus, Ser. No. 85,311.

In fire alarm signaling, wherein the transmitters are of the non-interfering succession type, it is well known that if in the event the coil of one of the non-interfering magnets were to become open, the non-interfering qualities of the transmitters were lost. It is therefore an object of this invention to provide a signaling transmitter such that in the event one of the non-interference coils therein should become open, the transmitter would still retain its non-interfering qualities.

It is further an object of this invention to provide a signaling arrangement so that a plurality of the signaling transmitters referred to herein may be utilized so that the signaling system will be materially improved in its operative effectiveness.

A further object is to provide positive operation of signal transmitting mechanisms and prevent the failure thereof due to an open coil in the non-interference magnet by providing an auxiliary electrical path to complete the circuit.

A further object of the invention is the provision of a coil and an alternate current path around the coil so that a plurality of these combinations may be included in a series circuit so that the opening of any coil or coils, will not disrupt electrical continuity of the series circuit.

A further object of the invention is to provide a signaling system comprising a plurality of serially connected signal transmitters having magnets for non-interference and other purposes and to provide these magnets with continuously effective current by-pass so that opening the winding of any magnet will cause the current to be diverted through its associated by-pass and avoid disruption of electrical continuity in the signaling system.

Other and further objects, and advantages of the invention will be hereinafter set forth and any novel features thereof defined by the appended claims.

For a better understanding of the invention reference may be had to the accompanying drawing, in which:

Fig. 1 is a schematic representation of central office equipment adaptable for use in conjunction with the present invention.

Fig. 2 is a different condition of the manually operated switch shown in Fig. 1.

Figs. 3 and 4 are diagrammatic representation of current paths in the signal transmitting unit when the circuit is closed through the door shunt switching device.

Fig. 5 is a modification of the shunts.

This invention relates not only to the normally closed metallic loop circuit but also provides advantages for use in conjunction with signaling circuits providing a ground return or auxiliary signaling conductor.

The diagrammatic representation shown in Fig. 1, has a suitable direct current energy source, here shown as a battery 103, connected across the lines L1—L2, with a register 101, connected in one side of the line. Two filters, such as condensers, are shown connected across the line to a common terminal 100, which terminal is connected to a conductor having impressed thereon a multiplicity of suitable alternating currents of different and distinct frequencies, from a multi-frequency alternating current energy unit 105, the other side of said alternating current unit being suitably connected to selective band pass filters 106, 107 and 108, and corresponding manifestation devices 106', 107' and 108' respectively, a filter and manifestation device being supplied for each of said frequencies, and responsive thereto. The other sides of the filter manifestation means are connected to a common return or line L3.

In Fig. 2 the switch is shown in a position to meet emergency signaling requirements, when one side of the line, as L1, becomes abnormally open. Battery 103, is connected serially between the lines L3 and L2 to supply energy for direct current operation. A low pass filter 104, is inserted in the line to permit passage therethrough of direct current, and to prohibit passage of alternating current and a consequential detrimental shunting of the alternating current central office apparatus.

The electrical current path may be best traced by referring to the drawing in Figs. 3 and 4, 45, which represent similar electrical parts and connections in a transmitter as contemplated by this invention, when the box shunt 95, is open and the door shunt is closed. In each of the views, lines L1, L2 and L3 are disposed so as to be used in 50 reference to similar line connections in Fig. 1, with the central office equipment.

In the patent to F. W. Cole, #1,058,728, and many other patents, the art shows it is old to establish a telegraphic communication from one 55

side of the metallic loop or line, and a ground, as an emergency circuit in case of a malcondition of the regular line. Once the emergency circuit is established the transmitter mechanism again 5 proceeds to seize the line in an attempt to reach the central station. Further it is well known in the art and further disclosed in the copending application Ser. No. 85,311, that a pair of movable contacts are periodically opened and closed 10 in response to the indentations of the station identifying code wheel. In Figs. 3 and 4 these movable contacts are referred to as contact sets 62 and 62'.

In regard to the establishing of the emergency 15 circuit the prior art discloses as in the Cole patent mentioned above, and also in the co-pending application Ser. No. 85,311, that it is well known to those skilled in the art how a circuit is established between the signal transmitter 20 and the auxiliary conductor or ground, the exact mechanism therefore, being immaterial to the present application. Suffice it to say that when the auxiliary circuit is completed, the member 25 84 engages the contact 85' which is merely symbolical of means for closing a circuit.

A direct current circuit path, Fig. 4, may be traced over line L1, from negative battery 103, Fig. 1, contact set 62, coil 98 and its shunt 99, to a terminal 141, through coil 98' and its shunt 99', 30 contact set 62', line L2, register 101, (Fig. 1), back to positive battery. When the code wheel actuates the contact sets 62—62', the direct current will be interrupted to transmit the station identifying code number corresponding to the 35 teeth on the code wheel, and actuate register 101.

In Fig. 3 since the impedance of the magnets 98—98' may be such as to be prohibitive to the 40 passage of alternating current, substantially none of the alternating current passes through the magnets, but does pass almost entirely through the magnet shunts. Switch 96 being closed, one frequency selected from a plurality of frequencies, by the selective band pass filter 133, passes from one side of the central office alternating current source, over lines L1—L2, through contact sets 45 62—62', resistors or shunts 99—99', unite at terminal 141, passes through 96 and filter 133, over L3, filter 106, actuating relay 106', back to the other side of the alternating current energy source. It will thus be seen that each impulse 50 of the code wheel circuit controlling contacts also controls an alternating current, to create a coded signal on the register 124, the initial impulsive current frequency of which is common 55 to all transmitters in the particular loop circuit and may be utilized by any "successful" transmitter.

A high pass filter 134 is connected across each 60 box shunt switch to provide alternating current circuit continuity to any waiting box, during operation of any successful transmitter to transmit an instantaneous signal. In Fig. 4, when the box is actuated, an instantaneous uncoded signal is received at headquarters, before the conventional 65 coded signal, regardless of whether or not the signaling loop is busy. Each transmitter has a selective filter 135, and an independent manifestation device and corresponding selective filter, two sets of which are shown in Fig. 1, as 107'—107 70 and 108'—108 respectively, and an independent alternating current of a distinctive frequency for each of said selective filter sets, originating in 105. Therefore, in Fig. 3 a current path may be traced from the alternating current energy source, 75 over L1—L2, to the signaling loop and trans-

mitters, to switch 97, selective filter 135, L3, back to the alternating current energy source.

An abnormal open circuit in the loop would cause the transmitter movement, as heretofore set forth, to actuate switch 84, Fig. 4, and close 5 a circuit between said switch and a contact 85'. Assume the abnormal open circuit occurred in the L1 side of the line. The switch 109 would then be changed automatically, or by a head-quarters attendant, to the position shown in 10 Fig. 2, whereby a direct current circuit path may be traced from positive battery, through register 101, line L2, contact set 62', magnet and shunt 98—99' respectively, terminal 141, contact 85', switch 84, low pass filter 136 which is prohibitive 15 to passage of alternating current but passes direct current over L3, back to negative battery. A low pass filter 104, is also shown in L3 in the central office apparatus, to prevent passage of 20 alternating current. The electromagnet 98' is so constituted as to permit normal operation on its single coil, the impulsion of contact set 62' would also interrupt an alternating current flow to effect actuation of register 124. The instantaneous uncoded signal would be received normally 25 as heretofore described.

By providing non-inductive shunting members for each magnet, the effective inductance of each parallel combination is substantially eliminated. Thus, if several transmitters are actuated at substantially the same instant, the contacts of the successful transmitter must make and break current in a circuit in which the magnets of all the waiting transmitters are serially connected. This added induction, in the signaling path tends to 35 hasten the deterioration of the signaling contacts, since the energy stored in all magnets must be dissipated in the form of an arc occurring at each separation of the cooperating signaling contacts. The shunting members, as herein disclosed, provide suitable and convenient means for absorbing 40 this energy of self-inductance and thus increase contact life.

At each closure of the signaling contacts, the 45 battery voltage is opposed by a counter electromotive force of self-inductance and the current gradually rises to a final value, i_0 which is equal

where e is the voltage of the battery and r is the 50 total resistance of the circuit. The current at any instant may be expressed:

$$i = i_0(1 - e^{-rt/L})$$

where e represents the base of natural logarithms, 55 t represents the elapsed time from the instant of closure of the contacts, r represents the total resistance in the circuit limiting the final current value i_0 , and L represents the total effective inductance in the circuit.

From this equation, the importance of the 60 ratio

$$\frac{L}{r}$$

will be seen since the time required for the current to attain only one-half of its final value will be:

$$t_{1/2} = 6931 \frac{L}{r}$$

seconds, and the time to attain $3/4$ of the final 70 value will be:

$$t_{3/4} = 1.3862 \frac{L}{r}$$

seconds, where L is the total effective inductance 75

of the circuit in henrys and r is the total resistance in ohms which limits the flow of current after the steady state has been reached.

In the construction of all transmitters of the positive non-interfering type, a definite time interval elapses between the instant of closure of the signaling contacts and the instant that the mechanical support is withdrawn from the non-interference armature. This action takes place as the contacts are closed by the sloping edge of each tooth on the code wheel. No such time interval is included or required when the contacts open since the overlapping action of the mechanism insures mechanical support for the armature prior to the opening of the contacts.

Thus, it will be seen that any successful transmitter must not only make and break the current flowing through all magnets in the circuit, but it must also include a period of overlap so that the current will attain a sufficient value to retain the non-interference armature in its portative position before mechanical support is withdrawn. If mechanical support would be withdrawn before sufficient electrical support is substituted therefore, the non-interference armature will drop back to its unattracted position and the transmitter will forfeit its control of the circuit.

Thus, if several transmitters are actuated simultaneously, or substantially so, each upon actuation introducing its non-interference magnets serially into the circuit, a condition may occur whereby no signal will be received from some of them. Upon actuation each transmitter includes its magnets in the series circuit connecting the several transmitters, thus increasing both the inductance and the resistance for the entire circuit. The introduction of the resistance reduces the final value of current, i_0 which will flow upon reaching the steady state. If the ratio,

$$\frac{L}{r}$$

is greater for the transmitter magnets than for the entire circuit, it will decrease the rate of current change when the signaling contacts close, and the combined retarding effect of several such magnets may in many cases be sufficient to delay the flow of current required to hold the non-interference armature of the successful transmitter in its portative position until after removal of mechanical support from said armature and its lapse into the unattracted position. Another of the transmitters, attempting to seize the line and transmit its signal, will in turn be similarly unsuccessful if its period of overlapping action is no longer than that of the first transmitter. Thus all of a group of transmitters will be unable to transmit their signals because of the excessive inductance in the circuit. It is probable, that after a considerable delay, during which certain transmitters will complete their cycle of operation and will have come to rest, shunting out their magnets, one or more of the group may succeed in transmitting their signals, but several signals will have been unnecessarily lost.

The provision of shunting members as described greatly reduces the effectiveness of the self-inductance of the magnets by permitting current to flow through the shunting members substantially instantaneously. Thus the presence of a plurality of non-interference magnets in the series circuit, introduced either by faulty contact at the movement shunts or by actuation of the respective transmitters, will exert no harmful de-

gree of retarding action upon the flow of signaling current.

These non-inductive shunting members have the further advantage of permitting the flow of heavy current surges, which may be induced by lightning or by adjacent power circuits, without damage to the magnets or the insulation of the system which would otherwise be caused by the extremely high voltages of self-induction accompanying rapid changes in current.

Figs. 3 and 4 show schematically a single transmitter connected in the loop circuit that is, between terminals L_1 and L_2 . However it is well known that several boxes may be, and usually are, connected serially in the loop circuit. While the drawing does not show specifically more than one box in the loop circuit, it is to be understood that this is done simply for the purpose of presenting a concise and clear explanation of the operation of the present invention, and it is to be understood that several boxes are serially connected in either or both sides of lines L_1 and L_2 .

While the drawing shows that the non-interference magnets each have a shunt which is made of carbon and therefore non-inductive, it is nevertheless true that under certain conditions the shunt for the individual magnets may be a coil, therefore, it is set forth herein, that the non-interference magnet may have any type of shunt which would permit functioning of the apparatus as contemplated by the present novel invention. The coil as a shunt for the non-interference magnet may be of any value capable of performing its desired objective.

The transmitter disclosed herein is shown connected to a circuit having an auxiliary return path, yet it is to be understood that this invention may be employed without the functions of the emergency switching means, for use on a system not provided with an auxiliary circuit return path, such as a ground.

When signaling on a system equipped for transmission over a metallic loop only, in the event of both coils of the non-interfering magnets having an open circuit in their respective windings, the signal would be sent, but the non-interfering succession feature would be suspended. Since the protective shunts are permanently connected across the coils, the necessity of providing mechanical motions and switching means is entirely eliminated by this novel invention.

If desired, many of the advantages of the invention may be realized without providing special shunt members as described above. Referring to Fig. 5, coils 98 and $98'$ are connected in multiple each serving as a shunt for the other. Utilizing this arrangement, substantially one-half the signaling current will flow through each winding. If either winding becomes open, circuit continuity will be maintained through the other, and in addition, the operative magnet will serve to perform the non-interference and succession functions. Furthermore, advantages of non-inductive shunts are approximated, since the inductive components of the magnet impedances are effective in the circuit as a parallel combination instead of the customary series combination heretofore employed. Thus, if magnets of the same inductance were used in either case, the total inductance of the parallel combination would be about one quarter of the inductance of the series combination.

For all practical purposes, however, the above described condition in which both non-inter-

ference magnets are electrically disabled, is extremely unlikely. First, the presence of the current by-passing elements, if of non-inductive design, will protect the magnets from one source of destructive influence, namely, surges induced in the fire alarm circuits by lightning and the like. Secondly, the probability that both magnets will be disabled simultaneously, and at a time when the transmitter is in operation for a fire, is exceedingly small, as compared to the possibility of a single magnet being inoperative condition.

If the transmitter is arranged, as contemplated above, so that effective non-interfering and succession functions may be performed under conditions of normal line current by either one of a pair of magnets, then the provision of the shunts will assure a novel and desirable feature, namely, the transmission of signals with complete non-interfering and succession operation, even though one of the magnets may be disabled.

In the present invention, voice currents and currents of like character will pass more freely through the shunting members, if of non-inductive design, thereby avoiding the necessity for providing additional apparatus for this purpose.

Certain specific detailed features and advantages of the invention have been herein set forth, but the invention is not limited thereto, as changes and alterations may be and may become apparent to those skilled in the art without departing from the spirit thereof as defined by the appended claims.

What I claim as new and desire to secure by Letters Patent of the United States is—

1. In signaling apparatus of the class described

having a current path, a non-interference electromagnet connected therein, said electromagnet comprising a multiplicity of serially connected coils, and an individual permanent by-pass for each of said coils each having characteristics allowing effective energization of its coil so that in the event one of said coils should become ineffective the non-interference properties of said electro-magnet will be retained.

2. In a signaling system comprising an energy source connected to a normally closed current path having a manifestation device therein, a multiplicity of non-interfering signal initiating stations serially connected in said path, a plurality of non-interference electro-magnets in each of said stations having a permanently connected shunt for each electromagnet each having characteristics allowing effective energization of its coil, so that in the event of an open circuit in one of said electromagnets, the non-interference signal operation of said initiating station will be maintained.

3. In a signaling system comprising an energy source connected to a normally closed current path having a manifestation device therein and a multiplicity of non-interfering signal initiating stations connected in said path; a plurality of non-interference electromagnets in each of said stations, a permanently connected shunt for each of the electromagnets, the resistance of the permanently connected shunt in each station across each electromagnet being such that the shunt will permit sufficient current to flow through the effective electromagnet windings to accomplish its non-interference functions.

PAUL P. HORNI.
